UNITED STATES PATENT OFFICE.

CARL HANGLEITER, OF MANNHEIM-WALDHOF, AND ADOLF SCHNEIDER, OF KEHLHEIM-ON-THE-DANUBE, GERMANY, ASSIGNEES TO ZELLSTOFFFABRIK WALDHOF, OF MANNHEIM-WALDHOF, GERMANY, A CORPORATION OF GERMANY.

METHOD OF AND SYSTEM FOR REGENERATING SULPHURIC ACID AND WASTE HEAT FROM SULPHITE CELLULOSE BOILERS.

Application filed April 3, 1922. Serial No. 549,112.

To all whom it may concern:

Be it known that we, CARL HANGLEITER and ADOLF SCHNEIDER, citizens of Germany, residing, respectively, at Mannheim-Waldhof and Kehlheim-on-the-Danube, Germany, have invented certain new and useful Improvements in Methods of and Systems for Regenerating Sulphuric Acid and Waste Heat from Sulphite Cellulose Boilers; and we do hereby declare the following to be a full, clear, and exact description of the invention, such as will enable others skilled in the art to which it appertains to make and use the same.

Our invention relates to improvements in the method of and system for regenerating sulphur dioxide and waste heat from sulphite cellulose boilers, and the object of the improvements is to provide a method and a system by means of which a high proportion of the said acid and waste heat is regenerated. With this object in view our invention consists in removing and precipitating the gas and vapor from the sulphite boiler in close proximity to the boiler by means of fresh lye. Thereby we are enabled to reduce the pressure of the gas or vapor to a minimum, so that also the loss of acid is reduced to a minimum.

In order that our invention be more clearly understood an example embodying the same will be described hereinafter, reference being had to the accompanying drawing showing a preferred system for putting the method into effect. In said drawing,

Fig. 1, is a diagrammatical plan view of the system, and

Figs. 2 and 3, are side views taken respectively on the lines 2—2 and 3—3 of Fig. 1.

Referring to the example shown in the figures, our improved system comprises a set of sulphite boilers A, B, . . . Y, and Z, conduits 4 and 5 mounted alongside the set of boilers and adapted to be connected with the top parts of the individual boilers through branch pipes a^1 , b^1 , . . . y^1 , and z^1 and valves a^2 , b^2 , . . . y^2 , and z^2 , and valves a^3 , b^3 , . . . y^3 , and z^3 , a tank 7 or 9 for fresh lye adapted to be connected with the conduit 5 respectively through a valve 8 and a valve 10, a pump 11, and a pipe 12, and a tank 14 communicating with both conduits 4 and 5.

As shown the tank 7 is disposed above the level of the conduit 5, and the tank 14 below the same, so that when opening the valve 8 the lye flows through the pipe 5 by gravity. The tank 9 is located below the level of the pipe 5, and the lye is raised into the same by means of the pump 11. It will be understood that ordinarily only one of the tanks 7 or 9 is provided, and where both tanks are provided only one of them need be in operation at a time.

The operation of the system is as follows: For removing the steam and sulphur dioxide SO_2 for example from the boilers B and Y located near the opposite ends of the conduits 4 and 5, the valves b_2 and y_2 are opened for establishing connection between the said boilers and the conduit 4, as is known in the art. Thereby the pressure within the boilers B and Y is reduced say to 2 atmospheres. Now the valves b_2 and y_2 are closed and the valves b_3 and y_3 opened, so that the boilers are connected through the branch pipes b_1 and y_1 with the conduit 5. Through the conduit 5 there flows cold fresh lye from the tank 7 or 9, so that the steam flowing into the conduit 5 is immediately condensed and the temperature of the sulphuric acid reduced so far that it is readily absorbed by the lye. This process is particularly effective because the lye passes the branch pipes at high velocity, so that a large volume of lye gets in contact with the steam and the sulphur dioxide and the bubbles of gas admixed with the lye continuously meet fresh particles of lye. Furthermore, by suddenly cooling the gas and condensing the steam a certain vacuum is produced whereby the gas is rapidly drawn from the boilers by suction.

Preferably the vertical part of the conduit 5 which is connected with the tank 14 includes a trap 13. The lye flows into the tank 14, and is finally saturated to the desired degree with sulphur dioxide. Preferably the volume of lye flowing through the pipe 5 is such that the volume thereof required in a boiler takes up the necessary heat and sulphuric acid. Thereby temperatures are avoided which might cause an objectionable pressure within the conduit 5.

From the foregoing description of the invention it will be understood that the pres-

sure within the boilers is reduced far beyond the degree attained in systems now in use in which the gas and steam are withdrawn through a conduit similar to the conduit 4. By connecting all the boilers to a common conduit similar to the conduit 4, the average pressure within the conduit is necessarily high, by reason of the difference of the pressures within the boilers, the resistance within the long conduit, and the liquid column within the receptacle 14 which must be overcome by the gas, and practically the pressure is not less than $2\frac{1}{2}$ atmospheres. This results in a loss of sulphur dioxide and heat. By reducing the pressure in close proximity to the boilers a suction is produced which is primarily transmitted to the individual boilers and is particularly effective by reason of the short length of the branch pipes.

We claim:

1. In a process for regenerating sulphur dioxide and waste heat from sulphite cellulose boilers, introducing the gas and vapor coming out of the boiler and while still hot at a point in close proximity to the boiler into streaming cold fresh lye.
2. In a process for regenerating sulphur dioxide and waste heat from sulphite cellulose boilers, introducing the gas and vapor coming out of the boiler and while still hot at a point in close proximity to the boiler into streaming cold fresh lye and introducing said lye into a closed receptacle.
3. In a system for regenerating sulphur dioxide and waste heat from sulphite cellulose boilers, a conduit for fresh lye lying in close proximity to the boiler, and on the boiler means for discharging gas and vapor directly and while still hot into said conduit.
4. In a system for regenerating sulphur dioxide and waste heat from sulphite cellulose boilers, a conduit for fresh lye, lying in close proximity to the boiler, on the boiler means for discharging gas and vapor di-

rectly and while still hot into said conduit, means for continuously supplying fresh lye to the conduit, and means for continuously emptying the conduit.

5. In a system for regenerating sulphur dioxide and waste heat from sulphite cellulose boilers, a conduit for fresh lye, lying in close proximity to the boiler, on the boiler branch pipes for discharging gas and vapor directly and while still hot into said conduit, a receptacle for continuously supplying fresh lye to the conduit, and a receptacle for continuously emptying the conduit.

6. In a system for regenerating sulphur dioxide and waste heat from sulphite cellulose boilers, a plurality of boilers, a common conduit for fresh lye mounted alongside said boilers in close proximity to the boilers, and on the boilers means for discharging gas and vapor directly and while still hot into said conduit.

7. In a system for regenerating sulphur dioxide and waste heat from sulphite cellulose boilers, a plurality of boilers, a common conduit for fresh lye mounted alongside said boilers in close proximity to the boilers, on the boiler means for discharging gas and vapor directly and while still hot into said conduit, means for continuously supplying fresh lye to the conduit, and means for continuously emptying the conduit.

8. In a system for regenerating sulphur dioxide and waste heat from sulphite cellulose boilers, a plurality of boilers, a common conduit for fresh lye mounted alongside said boilers, in close proximity to the boilers, on the boiler branch pipes for discharging gas and vapor directly and while still hot into said conduit, a receptacle for continuously supplying fresh lye to the conduit, and a receptacle for continuously emptying the conduit.

In testimony whereof we hereunto affix our signatures.

CARL HANGLEITER.
DR. ADOLF SCHNEIDER.
